ELECTRIC CUT-OUT

Olin Rittenhouse, Honeoye Falls, N. Y.

Application July 11, 1932, Serial No. 621,812

1 Claim. (Cl. 200—119)

This invention relates to electric cut-outs, and particularly to that kind of cut-out comprising a fuse plug and socket, said fuse plugs being designed to different electric loads corresponding to the maximum amperage of the circuit in which they are to be employed.

The principal object of this invention is the provision of cooperating sockets and plugs which are simple in construction, inexpensive to make, and which are so constructed that a plug of high amperage will not make the contact when used with a socket of low amperage, and vice versa.

To these and other ends, the invention consists in the construction and arrangement of parts that will appear from the following description when read in conjunction with the accompanying drawing, the novel features being pointed out in the claims at the end of the 20 specification.

In the drawing:

Fig. 1 is a central vertical section of a fuse plug constructed according to one possible embodiment of the invention;

Fig. 2 is a similar view of a cooperating socket;

Fig. 3 is a front elevation of a stud for adapting the plug shown in Fig. 1 for use with a socket of ordinary or usual construction;

Fig. 4 is a central vertical section of a plug 30 designed to be used with a socket in a circuit of different amperage from that shown in Fig. 1;

Fig. 5 is a central vertical section of a socket designed to cooperate with a plug such as that shown in Fig. 4;

Figs. 6 and 7 are views similar to Fig. 4 of plugs designed to carry loads of still different amperages, and

Figs. 8 and 9 are central vertical sections of sockets designed to cooperate respectively with 40 the plugs shown in Figs. 6 and 7.

Referring particularly to the drawing, the invention is illustrated applied to a cut-out of well known form, and comprises a socket 1 preferably constructed of suitable insulating material 45 having an opening or recess 2 in its upper face and a centrally arranged opening in its base communicating with the bottom of the opening 2 and preferably concentric therewith. This latter opening is internally threaded for cooperation with a post in the form of a headed screw 3 threaded therein from below. However, the post may be secured in the socket by any suitable means. The lower end of the opening may be counter bored, as shown, to receive the 55 head of the screw. One of the conductor termina-

nals 4 is connected with the screw and the outer or lower end of the opening may be sealed, as shown, with any suitable insulating material. The screw 3 projects into the opening 2 from its bottom, and has a sleeve 5 of high conductivity detachably threaded thereon, the upper end 6 of which serves as a terminal or contact point.

The opening or recess 2 has a threaded lining 7 of high conductivity secured therein, which is 65 connected with the other conductor 8 and serves as a terminal therefor. The plug 11, shown in Fig. 1 of the drawing, is constructed of suitable insulating material and comprises a knurled fingerpiece 12 at one end and its other end has 70 a centrally arranged opening 13 therein. A contact member 14 is seated in said opening which is connected with a threaded casing or thimble 15 of high conductivity secured on the outer wall of the plug. A fusible safety link 16 adapted 75 to carry an electric current of given amperage connects the contact 14 with the casing 15. The threaded casing 15 cooperates with the lining 7 in the socket when the plug is threaded therein. The distance from the contact member 14 to the lower end of the plug may be substantially the same as the length of the sleeve 5 or less, so that when the plug is screwed into the socket, the contact 14 contacts the upper end of the sleeve and closes the circuit between the 85 conductors 4 and 8 through the fusible safety link 16.

Means are provided for adapting the plug 11 for use with the ordinary socket having a contact at the bottom of the opening 2. To this end, 90 the lower or outer end of the opening 13 in the plug is threaded for cooperation with a stud 17, shown in Fig. 3, which may be threaded therein into contact with the contact 14 and at its outer end adapted to engage the contact at the bottom 95 of the socket opening.

The tubular members 5 may be made of various heights. Corresponding plugs 11 for cooperation therewith would have the contacts 14 arranged at various distances from the lower or inner end 100 of the plug to correspond to and cooperate with the socket contacts of different heights or elevations. In such a system, if a socket having its contact at lowest elevation were used in the circuit of least amperage, and the sockets having 105 contacts at higher elevation were progressively used in circuits of progressively greater amperage, none of the plugs except the one especially constructed for use therewith or one of lower amperage would serve to close its circuit, or in 110

other words, it would be impossible to use a plug of higher amperage than that for which it was designed in any of a plurality of circuits of different amperages; however, a plug of weaker 5 amperage might be inserted in a socket in a stronger circuit than that for which it was intended, but of course could not carry its full load. In such a system, it would be impossible to overload any circuit.

10 In Figs. 4, 6 and 7 are shown fuse plugs 21, 22 and 23 respectively, which are of well known type and similar to each other except that tabular portions 24, 25 and 26 are of different lengths for cooperation with contacts 27, 28 and 29 respectively in sockets 31, 32 and 33 similar to the 15 socket 1 in all respects, except that they are arranged at progressively greater distances from the bottom walls of the openings or recesses in the sockets. The contact 28 is arranged at the 20 least distance from the bottom wall of the opening and the greatest distance from the upper end thereof, and the contact 29 is at the greatest distance from the bottom wall of the opening in its 25 socket and nearest the upper end thereof, while the contact 28 is shown in an intermediate position.

The plugs shown in Figs. 4, 6 and 7 are not 30 interchangeable with the plug 11 in the socket 1 since the plugs engage the upper end of the sleeve and prevent the interengagement of the 35 threads on the plug with those in the socket. It is also impossible to close the circuit in any of the 40 sockets 31, 32 or 33 with the plug 11, since the

inner end of the plug engages the bottom of the opening in the socket or its fingerpiece engages the top of the socket before the contact closes the circuit. In a system comprising two circuits, such as domestic lighting systems which are 80 usually wired for either 15 or 30 amperes of current, one of the sockets shown in Figs. 5, 8 or 9 with its cooperating plug could be used in one of the circuits and the socket 1 and its cooperating plug 11 in the other, and neither plug would 85 fit a socket in the other circuit. In such a system, it is not only impossible to overload a circuit, but it is impossible to use a weaker fuse in a stronger circuit, which would "blow" as soon as the current became too strong for the fusible 90 link.

I claim:

The combination with a socket, of a fuse plug engageable therewith and having means at its outer end for limiting its movement into the 95 socket, the socket having a centrally arranged opening in its base, a post extending through said opening and projecting into the interior of the socket, said post having a head abutting the outer surface of the socket adjacent said opening, and a sleeve having threaded engagement 100 with the inner end of the post and abutting the inner surface of the socket adjacent said opening, said sleeve being of such length that its inner end makes contact with the inner end of 105 the plug when the latter is screwed into the socket to its innermost position.
